UNITED STATES PATENT OFFICE.

LOUIS LEHR, OF BAYONNE, NEW JERSEY, ASSIGNOR TO MEYEROWITZ MANUFACTURING COMPANY, INC., OF NEW YORK, N. Y., A CORPORATION OF NEW YORK.

FINGER-RING WITH INTERCHANGEABLE SIGNET-TOP.

1,216,471.

Specification of Letters Patent. Patented Feb. 20, 1917.

Application filed May 4, 1916. Serial No. 95,393.

To all whom it may concern:

Be it known that I, Louis LEHR, a citizen of the United States, residing at 33 West Fifty-first street, Bayonne, county of Hudson, and State of New Jersey, have invented certain new and useful Improvements in Finger-Rings with Interchangeable Signet-Tops, fully described and represented in the following specification and the accompanying drawings, forming a part of the same.

This invention relates to a ring having an initial signet-top upon the head; and the object of the invention is to furnish a means of providing such a ring with a signet-top bearing any initial desired.

This I effect by forming the head of the ring with a seat adapted to receive and support a signet-top, and providing a series of interchangeable signet-tops bearing the various initial letters, so that the dealer in such rings may fit to the ring any of the signet-tops which bear the right initial for a given purchaser.

The invention consists in forming the head of the ring with a seat to receive a signet-top and with a bridge below such seat, and providing the signet-top with a shank having an end fitted to secure in the bridge.

In the annexed drawing is illustrated a ring having an aperture extended through its head, and a dished bridge secured in the aperture with its edge below the margin of the head; whereby the margin forms a recess for a signet-top, and the edge of the bridge forms a seat for the same.

The bridge is perforated in the center, and the signet-tops are provided with a shank adapted to extend through the bridge, and having upon its inner end a bore or tongues to be expanded over the under side of the bridge to lock the signet-top in place.

In the drawing, Figure 1 shows the head of the ring in readiness to receive the signet-top; Fig. 2 shows the side of the ring with the signet-top inserted; Fig. 3 shows a signet-top bearing the letter D; Fig. 4 a signet-top bearing the letter S; Fig. 5 is a longitudinal section through the signet-top and the ring to which it is applied, with the shank of the signet-top extended through the bridge and its end made tubular to be easily expanded; Fig. 6 is a cross section of the ring showing the seat formed by the edge of the bridge and the end of the tubular shank expanded upon the inner side of the

bridge; Fig. 7 is a perspective view of the under side of the signet-top, showing a modification with the shank split to form prongs for bending over the under side of the bridge; and Fig. 8 shows the under side of the signet-top with such a split shank.

Figs. 5 to 8 are enlarged greatly beyond the natural size.

a designates the body of the ring, and *a'* the head having an aperture *c* extended through the same.

d is a bridge secured in the aperture by solder or other means, and having its edge fitted a little below the margin at the top of the head as shown in Fig. 6, such edge forming a seat *e* to support the signet-top *f*.

The center of the bridge is formed with a perforation *g*, and the signet-top is formed with a shank *h* adapted to extend through the perforation in the bridge, and the end of the shank is formed, as shown in Fig. 5, with a bore *i*, so as to be readily expanded or clenched upon the inner side of the bridge to lock the signet-top permanently thereon, as shown in Fig. 6.

Such expansion or clenching can be done with any conical tool by manual pressure, thus enabling a dealer in such rings to secure any signet-top in the head of the ring without any material labor.

In Figs. 3 and 4, two signet-tops of an alphabetical series are shown, the one in Fig. 3 bearing the initial D and that in Fig. 4 the initial S; and it is obvious that a dealer could select any one of a series of such signet-tops adapted to fit the seat *e*, and secure the same in the ring without any material labor or delay. A purchaser could thus be furnished with a ring bearing any desired initial, and without compelling the dealer to carry a large assortment of rings each having a different initial signet-top permanently secured therein.

By this invention the dealer may supply any purchaser with an initial ring by carrying in stock only a few of the rings and a suitable assortment of the desired initials.

The bridge *d* is shown dished in the drawing to simulate upon its under side the cutting of a seal gem, the under side of the bridge being brightly polished to present such an appearance.

Figs. 7 and 8 show the tubular end of the shank *h* split, so as to form tongues which

may be readily bent over upon the inner side of the bridge instead of expanding the bore of the shank.

It is apparent that all the signet-tops in the series must be provided with the shank *h* for securing any selected top on the seat of the ring.

Having thus set forth the nature of the invention what is claimed herein is:

- 10 1. A finger ring for receiving any one of a series of similar signet tops, the ring having an aperture extended through the same and a seat within the aperture, a signet top fitted to the said seat and provided with a shank, a perforated bridge secured in the aperture to receive the said shank, said signet top being permanently secured upon the seat by the said shank and bridge.
- 15 2. A finger ring for receiving interchangeable signet tops, the ring having a head with an aperture through the same, and a dished bridge secured in the aper-

ture forming a seat, a signet-top fitted to the said seat and provided with an expansible shank, the bridge being provided with a 25 perforation to receive the expansible shank and retain the signet-top permanently upon the seat when the end of the shank is expanded below the bridge.

3. A finger ring for receiving any one of a 30 series of similar signet-tops, and having a head with an aperture through the same, a dished bridge secured in the aperture with its edge below the upper margin of the head to form a seat, said bridge having a 35 perforation to receive a shank, and a signet-top fitted to the seat and having a shank with an expansible end extended through the said perforation and expanded below the bridge to retain the signet-top permanently 40 on the seat.

In testimony whereof I have hereunto set my hand.

LOUIS LEHR.
